UNITED STATES PATENT OFFICE.

WILLIAM H. ROBBINS, OF SPRINGFIELD, OHIO, ASSIGNOR TO THE WILLIAMS COMPANY, OF LONDON, OHIO, A CORPORATION OF OHIO.

DESIGN FOR A SCOURING DEVICE.

Application filed May 23, 1927. Serial No. 22,141. Term of patent 7 years.

To all whom it may concern:

Be it known that I, WILLIAM H. ROBBINS, a citizen of the United States, residing at Springfield, in the county of Clark and State of Ohio, have invented a new and ornamental Design for a Scouring Device, of which the following is a specification, reference being had to the accompanying drawing, forming a part thereof.

The design comprises a holder and a plu-

rality of steel wool pads which constitute a scouring device.

In the accompanying drawings:

Figure 1 is a perspective view of a scouring device showing my new design.

Figure 2 is a bottom plan view thereof.

I claim:

The ornamental design for a scouring device as shown.

WILLIAM H. ROBBINS.
